AUTOMOBILE REFRESHMENT TRAY

Clyde W. Morgan, Atlanta, Ga.

Application December 10, 1943, Serial No. 513,773

1 Claim. (Cl. 206—19.5)

1

Generically this invention relates to trays or slideable shelf-like structures, but it more particularly is directed to a refreshment tray assembly for attachment to the instrument panel structure of an automobile.

The principal object of this invention is the provision of a refreshment tray assembly for supporting beverage glasses, bottles, condiment containers and the like, for serving refreshments comprising a sleeve or jacket tray supporting member formed with rounded or curved side portions and a tray member formed with an integral bottom portion having upturned correspondingly curved side members, an upturned vertical end portion, and an end plate secured to and overlying said end portion, said tray adapted for telescopic engagement within said sleeve member, said end plate adapted to limit the insertable movement of the tray by engagement with the end of said sleeve, and disengageable coacting means between the sleeve and tray for normally preventing complete withdrawal of the tray from the sleeve.

A further object of this invention is the provision of a tray assembly of this character comprising a substantially rectangular sleeve member formed from one piece blank of suitable material bent upwardly and inwardly forming rounded or curved side portions with the free ends of said material in non-meeting engagement, forming a longitudinal slot in its upper surface, reinforcing strips of suitable material interconnecting said free edges at each end of the sleeve, and a tray formed from one piece of material having substantially similar dimensions telescopically engageable in said sleeve and formed with an integral turned up end wall, complementally curved upstanding side walls, said side walls adjacent the end wall being formed with inwardly projecting portions constituting condiment container holders.

With these and other objects in view, which will become apparent as the description proceeds, the invention resides in the construction, combination and arrangement of parts, herein-after more fully described and claimed, and illustrated in the accompanying drawings, in which like characters of reference indicate like parts throughout the several figures, of which:

Fig. 1 is a perspective view of the tray supporting sleeve.

Fig. 2 is a perspective view of the tray detached from the supporting sleeve.

Fig. 3 is an elevational view of the end plate removed from the tray.

In the illustrated embodiment characterizing this invention there is shown a substantially rectangular supporting sleeve or jacket member A, in the present instance, formed from a one-piece blank of metallic material with its opposite ends

2

bent upwardly and inwardly in such a manner as to form the bottom 1, rounded or curved side walls 2, and upper portions 3 extending in spaced parallelism with respect to the bottom 1 and with the free end edges 4 of said portions spaced apart to form the slot 5. Said portions 3 constituting the top 6 and are connected by the metallic reinforcing strips 7 of a length substantially corresponding to the width of the sleeve and are secured thereto by welding, soldering, riveting or in any suitable manner. Openings 8 are formed in said top 6 at one or both ends through which extend screws or other fastening elements for securing the sleeve to the under surface of the instrument board structure with its front end preferably flush therewith. For convenience in mounting the sleeve in supporting position slots 9 are formed in the bottom 1 through which a screw driver or other instrument may be inserted as will be well understood.

Suitably and hingedly secured to the front strip 7 within said slot 5 is a gravity operated T-shaped tray stop or anchor member 10 for normally preventing complete separation of the tray from the sleeve, as will directly more fully appear.

The tray B adapted for slideable telescopic engagement with respect to sleeve A, is formed from a one-piece strip of metal or the like bent to form the front end 11 extending upwardly at right angles with respect to the bottom 12 and the upwardly-extending side members 13 curved conforming to and adapted to slidably engage the inner surface of sides 2 of said sleeve A and preferably extend rearwardly beyond the rear bottom edge 14 of the tray as at 14' to prevent any tilting of the latter when in extreme extended position. The respective curved sides 13 terminate in the opposite inwardly extending edges 13' adapted to overhang the bottom 12 for a purpose directly more fully appearing. The bottom 12 is formed at its rear edge with a struck up portion 15 adapted to align with slot 5 when the tray is positioned in sleeve A and to constitute a stop member to engage the depending T-member 10 to prevent complete disengagement of the tray from the sleeve when said tray is moved outwardly in opening direction. To effect complete disengagement and removal of the tray, it is only necessary to lift or elevate the T-member 10 with a finger sufficiently to clear the stop 15, and pull the tray out, and it may be replaced by simply inserting it in the open end of the sleeve and sliding it therein, as the stop member 15 will automatically elevate the T-member and, as it passes, said member will fall to its initial tray stopping position, as will be well understood.

An end or face plate 16 is adapted to be superimposed on end 11 and is formed on its inner surface with countersunk threaded openings (not

shown) adapted to register with openings 17, in said end 11 and to receive the threaded ends of suitable screws extending through said openings 17. The dimensions of said face plate 16 are slightly greater than those of the end of sleeve A, so as to not only conceal said sleeve but to constitute a stop for limiting the insertable movement of the tray with respect to said sleeve. The exposed or outer surface is preferably ornamentally treated to match the finish of the instrument board to which the tray assembly is attached, and to form in most instances a continuation thereof.

Further, the curved side portions 13 are cut away at one end as at 18 to form portions 19 and providing the corner openings 19', said portions 19 being bent downwardly, and their free ends 20 slightly upwardly to bring them substantially into lateral positions within said corner openings, and are formed with openings 21 to receive salt and pepper or like condiment containers and constituting holders therefor. This construction not only positions the holders out of the way but does so without restricting the normal content supporting area of the tray and provides openings at opposite corners of said tray, thereby preventing accumulation of dirt therein and aiding the cleansing operation by permitting passage therethrough of water and the like.

It will be apparent that I have provided an automobile refreshment tray assembly or complete unit adapted to be attached to practically all automobile bodies now in use or built into new ones as they are manufactured, and the curved design of the side construction of the sleeve and tray not only adding to the strength thereof and the smoother substantially non-friction operation of the tray, but such design without corners provides a sanitary construction, easily cleansed with a cloth or napkins. Also the overhanging edges of the side walls of the tray by engaging the glasses or beverage bottles at points spaced from their bottoms tend to prevent their upsetting when in tilted positions owing to the uneven position of the tray by reason of the sloping terrain on which the automobile may be standing, such side wall construction lending itself particularly to the accommodation of glasses and bottles of varying configurations and with enlarged bottoms, and irrespective of which, maintains them in upright position.

It is further apparent that the coacting arrangement and detachable interconnection of the tray and sleeve is such that the engagement of sleeve T-stop or anchor member 10 when in engagement with the tray stop member 15 in conjunction with the rear extensions 14' of side 13 fitting in the enveloping side walls 2 and against the adjacent surface of top 6 forms a co-acting locking and bracing action constituting a rigid connection between the sleeve and tray preventing complete removal or vertical or lateral movement of the tray when in use.

From the above it will be apparent that I have provided an automobile refreshment tray assembly or unit embodying a supporting sleeve and telescoping tray of simple construction and pleasing appearance, and which may be constructed of metal, plastic or other suitable material, the rounded side edge formation not only adapted to reduce friction, enhance the smooth non-binding operation of the tray and prevent upsetting of the

refreshment glasses and bottles even though they may be of irregular shape and have enlarged bottom portions, but provides a sanitary easily cleaned structure, including condiment holders within the tray and at the same time removed from the contents supporting area, and also the coacting sleeve locking and tray stop features in conjunction with the tray rear end side construction effect a rigid interlocking and bracing of the tray in open position so as to support a capacity amount of refreshment contents without wobbling or tilting movement with respect to said sleeve even during normal travel movement of the automobile, yet simple in construction, easily installable, manufacturable at a minimum cost, and efficient for the purposes intended.

Although in practice I have found that the form of my invention illustrated in the accompanying drawings and referred to in the above description as the preferred embodiment is most efficient and practical, yet realizing that conditions concurrent with the adoption of my invention will necessarily vary, I desire to emphasize that various changes in details of construction, proportion and arrangement of parts, may be resorted to within the scope of the appended claim without departing from or sacrificing any of the principles of this invention.

Having thus described my invention, what I desire protected by letters patent is as set forth in the following claim:

A refreshment tray assembly for automobiles adapted to support beverage glasses and bottles carried thereby in upright position comprising an attachable sleeve structure formed with curved sides, a tray formed with a bottom, an end member, curved side members conforming to and adapted to slidably engage in the sides of said sleeve, said members being formed with inwardly extending overhanging edges adapted to supportingly engage the sides of beverage glasses and bottles supported by the tray to maintain them in upright positions irrespective of their configurations, the ends of said side members adjacent to the end member being formed with struck down apertured portions constituting holders adapted to receive condiment containers, such construction providing openings in which said holders are positioned off-set with respect to the normal contents supporting area of the tray, and coacting means between the sleeve and tray to normally prevent complete disengagement of the tray when in extended position.
